UNITED STATES PATENT OFFICE.

GUSTAV J. GRAEBERT, OF DETROIT, MICHIGAN.

STEAM-TRAP.

SPECIFICATION forming part of Letters Patent No. 408,176, dated July 30, 1889.

Application filed November 20, 1888. Serial No. 291,385. (No model.)

To all whom it may concern:

Be it known that I, GUSTAV J. GRAEBERT, a citizen of the United States, residing at Detroit, county of Wayne, State of Michigan, 5 have invented a certain new and useful Improvement in Steam-Traps; and I declare the following to be a full, clear, and exact description of the invention, such as will enable others skilled in the art to which it appertains to 10 make and use the same, reference being had to the accompanying drawings, which form a part of this specification.

My invention relates to certain new and useful improvements in steam-traps, and has for 15 its objects, first, an improved trap for discharging the condensed water to a tank, sewer, or waste-pipe, and, second, certain modifications of the device, whereby the condensed water may be returned to a boiler, the trap 20 in its essential features being thus adapted for high or low pressure.

I carry out my invention as more fully illustrated in the accompanying drawings, and more particularly pointed out in the following 25 description and claims.

In the drawings, Figure 1 is a vertical longitudinal section of a device embodying my invention, showing the outlet-valve closed. Fig. 2 is a similar view showing the relation 30 of parts when the outlet-valve is opened. Fig. 3 illustrates a modification adapting the trap for the return of the condensed water to a boiler against steam-pressure.

I accomplish my invention as follows: 35 A represents a condensing-chamber of any suitable construction, the case A' of said chamber being of any desired form and arrangement.

B is the inlet-pipe leading to the steam- 40 pipe to be trapped, and preferably provided on the inner end with a downwardly extended or pointed nozzle b.

C denotes the discharge-pipe. The inlet-pipe is preferably led into the condensing- 45 chamber toward the top thereof, and the discharge-pipe is led therefrom toward the base, as shown.

D indicates a valve, of any suitable description, located within the discharge-pipe and 50 within the condensing-chamber and provided with a valve-stem d. As shown, the valve consists of a double-seated valve.

E is a supporting-arm, which may be conveniently engaged upon the valve-case. An inner receiving-basin F, provided with a 55 weighted arm F', is journaled upon the supporting-arm, as shown at f, said arm being engaged with the valve-stem to open and close the valve with the tilting of the arm and basin. The basin is arranged to receive the 60 condensed water through the inlet-pipe B, and is provided with an outlet f' and controlling-valve f², of any proper construction. In this instance, as shown, said controlling-valve is provided with an extended stem f³, which may 65 be provided, in turn, with a pin f⁴, to prevent the dislocation of the valve.

The operation of my invention as so far described will be readily understood. The condensed water enters the basin F and is received therein until its weight overbalances the weight upon the arm F', when the basin descends, the stem of the controlling-valve striking the base of the receiving or condensing chamber A. Simultaneously the rear end 70 of the arm F' is lifted, thereby opening the valve D, permitting the water to discharge 75 through the pipe C. The casing A' may be provided with a discharge-opening and removable stopper a, to effect the thorough 80 emptying of the condensing-chamber, when desired. In case the water from the condensing-chamber is to be returned to the boiler, I locate within the discharge-pipe a suitable 85 check-valve G, and also a suitable check-valve H in the inlet-pipe to prevent any back action of steam-pressure from the boiler. I prefer, moreover, for such an object to locate within the discharge-pipe or valve-casing connected therewith a conical pipe I, while the 90 said pipe is also provided with an inlet-opening c. A live-steam pipe J is led to the casing of the valve D. It will be apparent thus that when the basin is tilted and the valve D opened live steam will rush past the valve 95 and through the conical pipe I, causing a suction through the opening c, whereby the condensed water will be forced or drawn from the condensing-chamber, the pressure upon the check-valve G being equalized. The construction is simple and economical, and not liable 100 to easily get out of order.

The check-valves G and H, together with the live-steam pipe and conical pipe I, may

or may not be employed within the scope of my invention. The conical pipe I serves to discharge the steam into the discharge-pipe in a jet over the inlet c, thereby effectually producing the results described.

What I claim as my invention is—

1. In a steam-trap, the combination, with the condensing-chamber provided with an inlet and a discharge pipe, of a valve located in the discharge-pipe, and a tilting receiving-basin engaged to operate said valve, substantially as described.

2. In a steam-trap, the combination, with the condensing-chamber provided with an inlet and a discharge pipe, of a valve controlling communication through the discharge-pipe and provided with a valve-stem, and a tilting receiving-basin provided with a weighted arm engaged with said valve-stem, said basin provided with an outlet and controlling valve, substantially as set forth.

3. In a steam-trap, the combination, with a condensing-chamber provided with an inlet and a discharge pipe, of a valve D, to control communication through the discharge-pipe, a tilting receiving-basin engaged to operate said valve, a live-steam pipe communicating with the discharge-pipe through said valve, and a

check-valve G, located in the discharge-pipe, substantially as set forth.

4. In a steam-trap, the combination, with the condensing-chamber provided with an inlet and a discharge pipe, of a valve D, to control communication through the discharge-pipe, a tilting receiving-basin engaged to operate said valve, check-valves G and H, located in the discharge and inlet pipes, respectively, and a live-steam pipe communicating with the discharge-pipe through the valve D, substantially as set forth.

5. In a steam-trap, the combination, with the condensing-chamber provided with an inlet and a discharge pipe, of a valve D, to control communication through the discharge-pipe, a tilting receiving-basin engaged to operate said valve, a live-steam pipe communicating with the discharge-pipe through the valve D, said discharge-pipe provided with an inlet-opening, a conical point, and a check-valve G, substantially as described.

In testimony whereof I sign this specification in the presence of two witnesses.

GUSTAV J. GRAEBERT.
